Application April 2, 1943, Serial No. 481,546

11 Claims. (Cl. 74—125.5)

1

This invention relates to apparatus for indicating and recording the course of a vehicle.

The principal object of the invention is to provide improvements in such apparatus to the end that its usefulness and reliability may be increased. In carrying out the objects of the invention, a table or carrier is provided which receives a map or paper (ruled or blank) and has a scribe or stylus cooperating therewith for recording the location of the vehicle on the map or paper. The scribe is moved across the surface of the map under control of an integrating mechanism of an improved form which receives the directional data from a compass and data respecting distance traveled from the driving means of the vehicle.

A particular object of the invention is to provide improved integrating mechanism for resolving the movement or course of the vehicle into cardinal components which includes a disk or wheel, which is rotated by pawl mechanism driven at a rate depending on the speed of the vehicle, the effective movements of the pawl mechanism depending on the magnitude of the particular component of the direction of movement, so that the movement registered is dependent on the component of the speed.

A further object of the invention resides in the provision of improved ratio connections between the integrating mechanism and the scribe, which has incorporated therein variably adjustable devices to accommodate a greater range of map scales than has heretofore been possible.

A still further object of the invention resides in the provision of improved mechanism for obtaining a reading of the directional compass position and adjusting the integrating mechanism accordingly, which includes devices for continuously hunting within a predetermined angular range to ascertain the compass needle position, such continuous hunting action to also be applied to the mechanism which controls the effective movement of the integrating pawls to thereby produce an averaging effect, which is highly advantageous in contributing to the accuracy of the apparatus.

A still further object resides in the provision of improved mechanism for effecting an initial orientation of the apparatus to correct for the variation between true and magnetic north to the end that the vehicle's course will be correctly plotted on maps prepared in accordance with true north indications.

Other objects of the invention will be pointed out in the following description and claims and

2

illustrated in the accompanying drawings, which disclose, by way of example, the principle of the invention and the best mode, which has been contemplated, of applying that principle.

5 In the drawings:

Fig. 1 is a plan view of one end of the apparatus with parts at left broken away.

Fig. 2 is a plan view of the opposite end with parts at both sides removed, with Figs. 1 and 2 taken together constituting a plan view of the lower section of the device when placed one above the other in the order named.

Fig. 3 is an end view of the device showing the map scale adjusting mechanism, the view looking in the direction of the lines 3—3 in Fig. 2.

Fig. 4 is a section taken along lines 4—4 of Fig. 2, showing the interior of the map scale ratio adjusting devices.

Fig. 5 is a longitudinal section of the parts shown in Fig. 2, substantially along the lines 5—5 of Fig. 2.

Fig. 6 is a sectional view taken along lines 6—6 of Fig. 4.

Fig. 7 is a sectional view taken along lines 7—7 of Fig. 4.

Fig. 8 is a section taken along lines 8—8 of Fig. 6.

Fig. 9 is a detail showing the map scale dial, the view being taken along lines 9—9 of Fig. 2.

Fig. 10 is a sectional view taken substantially along lines 10—10 of Fig. 2.

Fig. 11 is a sectional view taken substantially along lines 11—11 of Fig. 2.

Fig. 12 is a plan section taken along lines 12—12 of Fig. 10.

Fig. 13 is a view showing certain of the parts of Fig. 12 in a different position.

Fig. 14 is a transverse section taken substantially along the lines 14—14 of Fig. 1.

Fig. 15 is a sectional detail of the driving connections to the compass.

Fig. 16 is a sectional view taken along lines 16—16 of Fig. 15.

Fig. 17 is a detail taken along the lines 17—17 of Fig. 1.

Fig. 18 is a detail of the counters, the view being taken substantially along lines 18—18 of Fig. 1.

Fig. 19 is a detail showing the compass reading devices, their manner of connection to the integrating mechanism, and the clutch controlling circuit connections.

Fig. 20 is a detail of a shutter mechanism, the section being substantially along lines 20—20 of Fig. 18.

Fig. 20a is a detail section along lines 20a—20a of Fig. 18.

Fig. 21 is a sectional elevation of the scribing carriage and its operating mechanism.

Fig. 22 is a plan view of part of the map table showing the relationship therewith of the scribe or pencil carriage.

Fig. 23 is a detail taken along lines 23—23 of Fig. 22, showing the north-south lead screw and the manner of connecting the carriage thereto.

Fig. 24 is a detail section taken along line 24—24 of Fig. 22 showing the pencil holder and the manner of connecting the same to the east-west lead screw.

Figs. 1 and 2, when placed one above the other, provide a picture of the plan view of the mechanism beneath the map table. It shows the compass connection at the upper end with the counters or indicators, while Fig. 2 shows the location of the integrating mechanism in the upper part and the map scale ratio adjusting mechanism in the lower part of the figure.

Drive mechanism.—The motor 10 (Fig. 1) is provided and is constantly in operation through connection to a suitable source of current in the vehicle. The motor pinion 11 drives the gear 12 integral with a pinion 13 which in turn drives a gear 14 secured to a cross-shaft 15. This shaft at its opposite end carries a gear 16 (see Fig. 17) which meshes with a clutch driving gear 17. At an intermediate point along shaft 15 is a gear 18 which drives an idler 19 which is in mesh with a clutch driving gear 20. Both clutch driving gears 17 and 20 are freely carried by a cross rod 21 and are constrained against axial movement on the rod, and through the gear connections just traced it will be observed that the gears 17 and 20 rotate constantly but in opposite direction. Intermediate the two gears and freely rotatable on shaft 21 is a pair of gears 22 slidable along the shaft into frictional engagement with either of the driving gears 17 or 20, the faces of the latter being provided with suitable frictional material for driving action.

Bell crank yoke 23 pivoted at 24 (Fig. 1) may be rocked in one direction by a magnet 25 and in the opposite direction by a magnet 26. When the device is in operation, one or the other of the magnets will be in operation, i. e., energized, so that there is driving connection between its related gear 22 and one of the driving gears 17 or 20. The gears 22 have connection with a pair of gears 27 secured on a cross rod 28, to one end of which is secured bevel pinion 29 which meshes with a bevel gear 30 on shaft 31, with the result that shaft 31 is rotated in either direction depending upon which of the two magnets is energized. As will be presently pointed out, when the vehicle is traveling along a straight line, the magnets 25 and 26 are alternately energized so that through the driving connections traced the shaft 31 receives an oscillatory motion, which is transmitted in one direction to the compass sensing devices and in the other direction to the integrating mechanism.

Compass sensing mechanism.—Tracing first the connections to the compass, the shaft 31 carries the pinion 32 (see Figs. 15 and 16) which meshes with a differential pinion 33 which in turn drives pinion 34 to drive a pinion 35 on shaft 36, which is coaxial with the shaft 31. During the operation of the device, the centers of the pinions 33 and 34 are stationary, so that shaft 36 is oscillated through the same angle as shaft 31 but in the opposite direction. The shaft 36 carries a bevel

gear 37 meshing with bevel gear 38 secured to the end of a flexible shaft 39 which extends to the compass. In Fig. 19 is shown diagrammatically the controlling mechanism for the magnets 25 and 26.

Inasmuch as the particular form of compass and the reading means therefor form no part of the present invention, it is sufficient to indicate simply the compass needle 40 upon which is secured a mirror 41, so that the mirror rotates with the compass needle. In the plane of the mirror there are provided a pair of light responsive cells 42 and a light source 43. With the mirror in position to reflect light from source 43 to one of the cells, electronic control circuits (which per se are also no part of the present invention) amplify the current from the cell to cause energization of one of the magnets 25 or 26 and, when the mirror is in position to reflect light upon the other cell, the second magnet would be energized. The cells 42 and light source 43 are mounted upon a gear 45 meshing with a gear 46 which is carried by the end of the flexible shaft 39 which, as has been explained, is capable of rotation in either direction.

When the mechanism is started, the compass sensing assembly comprising the cells and light source may be standing in any position, while the magnetic needle is directed toward the north pole and controlling the position of the mirror 41. The electronic control devices will cause one of the clutch magnets to energize, thus coupling the shaft 39 for rotation in one direction. The manner in which this is effected will now be briefly set forth. The clutch magnets 25 and 26 are operated by gas filled tubes, designated A and B respectively in Fig. 19, of the type known as 2050 tubes. At the instant current is switched on and with mirror 41 out of light reflecting position, there is no current flow in the plate circuits of the tubes and the cathodes and control grids of both tubes are at the same potential. Current therefore tends to flow through both tubes, but due to the unequal electrical characteristics of the tubes current is established in the plate circuit of one of the tubes before it is established in the plate circuit of the other tube. Assuming that such current flow is established in the plate circuit of tube A and thereby energizing magnet 25, such energizing circuit is traceable from negative side of source of 200 volts D. C., through a variable resistor C, cathode of tube A, plate of tube A, and magnet 25 to positive side of source.

The current flow through this circuit causes a voltage drop in the resistor C, whereby the potential control grid of tube B is made negative, thereby preventing establishment of current through this tube. Also, due to this action the plate of condenser D connected to magnet 25 is made negative and the plate of the condenser connected to magnet 26 is made positive. With magnet 25 energized, the gear 45 carrying cells 42 and light 43 rotates. The direction of the initial movement of rotation is immaterial, and it continues until the sensing assembly moves into the position for example, that shown in Fig. 19, wherein its relation to the mirror causes reflection of light upon one of the cells 42 (the cell connected to tube B for the assumption made above). The photocell upon thus becoming conductive effects the controls of the electronic unit which will result in energization of the alternate clutch magnet 26.

Since tubes A and B are gas filled, they remain energized until their plate circuits are brought to

a negative potential. Thus, the initial direction of rotation under control of tube A continues until light falls upon the cell of tube B. Then tube B becomes conductive and current from 90 volt source is applied to the cell and control grid of tube B, rendering this tube conductive and causing current to flow in its plate circuit to energize clutch magnet 26. Current flow in the plate circuit of tube B applies a negative bias to the control grid of tube A and incidentally causes condenser D to discharge. This causes the plate current in tube A to become negative, deenergizing magnet 25, and the negative bias now being applied to the control grid of tube A this tube cannot be fired.

With current now established in the plate circuit of tube B, magnet 26 is energized. The resulting shift in driving direction of the clutch causes the sensing assembly to now move in the opposite direction. If the compass needle 40 has not moved in the interim, the photocells and lamp will turn substantially 10° (exaggerated in Fig. 19), at which time the reflected light beam will strike the opposite or the alternate photocell. This causes operation of the electronic unit to bring about energization of the alternate clutch magnet, reversing the direction of rotation of the sensing assembly a second time to effect a reversion to the original direction of rotation.

In this manner as long as magnetic needle 40 remains motionless, the sensing assembly will continue to oscillate or hunt through an angle of approximately 10° equally divided on either side of the true position of the needle, and the gearing from the drive motor is such that the oscillating will occur at a rate of about 150 reversals per minute. As soon as any change occurs in the position of the needle, the photocell control causes the sensing assembly to follow the needle until it is overtaken in its new position, after which the continuous hunting action resumes. Briefly, then, shaft 39 and the shaft 31, which is geared to it, will move in one direction or the other to follow the direction of movement of the compass needle, and having reached such position will oscillate within the limits prescribed.

Referring now to Figs. 1 and 14, shaft 31 has a gear 61 thereon which through a train of gears generally designated 62 drives a rod 63, which in turn through bevel gear connection 64 drives a vertical rod 65, so that as the shaft 31 oscillates or turns the vertical rod 65 will go through the same motion. Secured to the upper end of this rod is a bifurcated lever 66 between whose separate arms is a pointer 67 normally restrained against movement by a suitable friction spring 68. This pointer indicates the course of the vehicle and its position is read on a dial 69 suitably graduated in degrees. This dial is rotatable on shaft 65 and has integral therewith a gear 70, so that through a train of meshing gears generally designated 71 the dial may be rotated by means of a knob 72. When magnetic north and true north coincide, the dial 69 is adjusted so that its north graduation is in line with a marker 73 scribed in a supporting plate. Where there is a variation between true and magnetic north, the angle of declination is entered into the device by manually rotating the dial 69 the appropriate angle with respect to line 73. In order to adjust for a west declination, the knob 72 is turned in such a direction that the zero or north mark of the dial 69 moves to the west the appropriate number of degrees, and for an east declination it is rotated in the opposite direction.

Referring to Fig. 14, the knob 72 by means of which the declination adjustment is made carries a bevel gear 74 at its lower end (see also Fig. 15), which through a bevel gear 75 rotates a gear 76 meshing with gear teeth of the differential cage 77 upon which the pinions 33 and 34 are mounted. The effect of rotating knob 72 is to also rotate the cage 77. Assuming the driven gear 35 of the differential to be stationary, rotation of the cage 77 will cause rotation of gear 32 and its shaft 31, the amount of angular displacement being in accordance with the extent to which the knob 72 is turned. This relative rotation introduces the angle of declination into the integrating mechanism. This adjustment of the position of the shaft 31 is transmitted through the gearing 62 (Fig. 14) to the pointer 67, the direction of rotation of the various gears being such that, when the disk 69 moves in one direction, the pointer will turn in the same direction.

After the adjustment for the angle of declination has been made, the pointer 67 will always extend in the direction in which the vehicle is moving and the bifurcated lever 66 will oscillate back and forth through a 10° angle in accompaniment with the oscillation of the compass sensing assembly. There is sufficient clearance provided between the arms of lever 66 and pointer 67 so that, where the vehicle is moving along a straight line, the pointer will not be disturbed. Briefly, to make adjustment for a west declination, the knob 72 is turned so that the zero or N mark of the dial 69 moves the required number of degrees counterclockwise from the fixed mark 73. The pointer 67 is also moved counterclockwise the same amount, so that the reading of the pointer on the dial is the magnetic bearing. For east declinations, the adjustment is, of course, in the opposite direction.

Integrating mechanism.—Referring now to Figs. 1, 2 and 12, the main oscillating shaft 31 carries a gear 78 which meshes with gear 79 secured to a shaft 80, upon which is secured a worm 81 which in turn drives a worm wheel 82 (see also Fig. 11) which drives a vertical shaft 83. Thus, the shaft 83 also oscillates when the vehicle is following a straight line and rotates when the course of the vehicle changes. At the upper end of shaft 83 there is secured a so-called sine disk 84 and at the lower end is a similar so-called cosine disk designated 85. These two disks 84 and 85 resolve the direction of movement of the vehicle into two components. Disk 84 is associated with the north-south components and the disk 85 is associated with east-west components. Each disk carries a pivoted block designated 86 which are displaced 90° with respect to the two disks. The block 86 of disk 84 rides in a slotted member 87 which is provided with rollers 88 supported in a stationary track 89 (see also Fig. 2).

The block 86 of the lower disk 85 controls an exactly similar member designated 90 which also is provided with rollers 91 guided in a stationary track 95. Each of the members 87 and 90 has adjustably fastened thereto a rack, that for the north-south disk being designated 93 and the one for the east-west disk being designated 94. The rack 93 drives a gear 95 (see also Fig. 10). This gear 95 has sleeve connection 96 with a shield 97 (Fig. 12), wherein the configuration of the shield 97 is shown. Immediately adjacent to shield 97 is a fixed or stationary shield 98 with cut-out portions arranged so that, as shield 97 is rotated

under control of the gear and rack connection from the north-south disk 84, a varying number of ratchet teeth in each of a pair of ratchets 89 and 100 (see Figs. 10 and 13) will be exposed for cooperation with sets of pawls 122 and 125. Shield 97 has a portion of smaller radius cut for approximately one-fourth of its circumference, the remainder of the shield being of larger radius as shown in Fig. 12. The stationary disk 98 has two sections of a radius equal to the smaller radius of disk 97 so that, when disk 97 is rotated to substantially 180° from the position shown in Fig. 12, the ratchet teeth exposed will be in a position diametrically opposite to that shown in Fig. 12.

Tracing the relative position of the parts, when the pointer 67 indicates the vehicle is traveling due north, the north-south disk 84 which is geared to the pointer through the connections traced will occupy a position, where the pivot block 86 (Fig. 2) lies along the horizontal axis of the disk, 90° in a counterclockwise direction from the position shown in Fig. 2. Accordingly, the rack 93 will be in its farthest position toward the left and, when in such position, the low portion of the shield 97 (Fig. 12) will be in substantial alignment with the corresponding right hand low portion of the stationary shield 98, so that the maximum possible number of ratchet teeth are exposed. When the vehicle is headed south, disk 84 will have the pin 86 in a position 90° in a clockwise direction from the position shown in Fig. 2 or 180° from the due north position. As a result, the shield 97 will have its low portion coinciding with the left hand low portion of shield 98 (Fig. 12) to expose the maximum number of ratchet teeth on that side of the stationary shield.

In any other position of the north-south disk 84, the disk 97 and shield 98 will jointly expose a lesser number of ratchet teeth. Thus, if the course of the vehicle is southeast or southwest, the teeth will be exposed as shown in Fig. 12, while if the vehicle is traveling northeast or northwest, the ratchet teeth will be exposed on the opposite side as indicated in Fig. 13. It is to be noted that, if the vehicle is traveling east or west, the low portion of shield 97 will coincide with one or the other of the high portions of shield 98, so that no ratchet teeth are exposed under such circumstances.

Through substantially identical mechanism the east-west disk 85 also effects the adjustment of a shield designated 101 (Fig. 10). The driving connection is from rack 94 (Figs. 10 and 11) to gear 102, sleeve 103 to the shield 101, adjacent to which there is a stationary shield 104 corresponding to the upper stationary shield 98. These two shields by their relative positions will expose a greater or lesser number of teeth in a pair of ratchets designated 105 and 106. The previously explained declination adjustment of pointer 67 is also made on the disks 84 and 85, through shaft 31 to which both pointer and disks are connected, so that the angle of exposed ratchet teeth will be in relation to true north.

Referring now to Fig. 10, a flexible cable 107 is driven from the vehicle at a rate proportional to the speed of the vehicle. Connected to the cable is a bevel gear 108 which drives a bevel gear 109 on a vertical shaft 110, to which is secured a ratchet 111 (see Fig. 12). The ratchet 111 drives a spring pressed pawl 112 pivoted on a disk 113, which disk is integral with a gear 114 which through gearing generally designated 115

drives a large gear 116. Means is provided for uncoupling this drive, which means constitutes a manually operated slide 117 which, when moved toward the left as viewed in Fig. 10, will rock a pivoted plate 118 clockwise to bring a conical ring 119 into engagement with a conical pin 120 in the pawl 112 to cam the latter out of engagement with the ratchet 111.

Referring now to Fig. 12, the gear 116 which is at rest when the vehicle is not in motion and which rotates in accordance with the speed of the vehicle has pivoted thereon four pairs of pawls on its upper surface and four like pairs of pawls on its lower surface. Considering the pawls

15 on the upper surface, the four pairs are exactly the same so that explanation of one pair will suffice for the others. What is known as the north pawl is designated 121, while the other, the south pawl, is designated 122. They are pivoted at 123 and are spring urged against a pin 124 in a follower arm 125. As the gear 116 rotates, the follower arm 125, which is sufficient in width to extend across both the shields 97 and 98, will ride on the peripheries thereof (see Fig. 5) and the high portion of either of the shields will hold the arm in such position that its pin 124 will maintain both the pawls 121 and 122 out of engagement with the ratchets 89 and 100, the pawl 122 being in the plane of ratchet 89 and the pawl 121 being in the plane of ratchet 100.

Where there is coincidence of low portions of the two shields, the arm 125 will permit the pair of pawls to move toward their respective ratchets. Provision is made, however, so that the two ratchets of the pair cannot at any time concurrently engage the related ratchets. For this purpose each pawl is provided with a tail lying in the plane of fixed cams which are generally designated 126 (Fig. 12). These cams are so positioned that the north pawl 121 is held in the position shown in Fig. 12 during the period that the pawl is moving through a sector, wherein ratchet teeth would be exposed if the direction of the vehicle were south or a component of its direction is south.

Similarly, as shown in Fig. 13, the south pawl 122 is held out of engagement with ratchet teeth as it passes through a sector in which teeth would be exposed as a result of the direction of the vehicle's travel being north as one component. Thus, assuming, for example, as in Fig. 12 the position of the shields 97 and 98 exposes a number of teeth, which represent that the vehicle is traveling in a direction of which south is a component, then as the gear 116 rotates, each pawl 122 will in turn drop into the first exposed tooth of the ratchet 98 and drive the ratchet with gear 116 until the pawl is lifted out of engagement with the ratchet due to arm 125 riding on to the high portion of the fixed shield 98. During such driving engagement, the north pawl 121 is held out by the lower of the cams 126. If the vehicle were traveling in the opposite direction, ratchet teeth would be exposed as in Fig. 13, wherein as gear 116 rotates, the north pawl 121 will drop into engagement with the first exposed tooth to drive the ratchet 100 until disengaged by the arm 125 riding up on the high portion of the stationary shield 98.

During this period of engagement, the upper cam 126 will hold the south pawl 122 out of active position. It will be noted in Figs. 12 and 13 that the amount that either ratchet is advanced is proportional to the integral number of teeth of the ratchet. Thus, the movable shield may vary

in its angular position almost the distance between two adjacent ratchet teeth, and the amount the ratchet will be rotated would be the same for any position between such limits. By reason of the oscillating or hunting action hereinabove explained, there is brought about an interpolation where the opening provided by the shields is not in accordance with an exact multiple of the ratchet teeth.

As explained, the disk 84 is continuously oscillated through a small angle, and as a result through the connections traced the movable shield 97 receives this oscillation which on the shield itself approximates a ratchet tooth space. It was also explained that this oscillation is fairly rapid, being in the neighborhood of 150 reversals per minute. Thus, where, for example, let us say 5½ ratchet teeth are exposed, the ratchet would be moved through five teeth as one pawl drives it and, as successive pawls drive it, the oscillation of the shield 97 would at times expose the teeth sufficiently to drive six and at other times sufficiently to drive only four. The percentage of number of times that four, five or six teeth are driven that will result over a period of time is proportional to the percentages of the four, five and six tooth space included in the total number of times the ratchet is driven.

Referring to Figs. 5 and 10, the underside of gear 116 carries four pairs of pawls exactly similar to the pawls described on the upper side of the gear which cooperate with the ratchets 105 and 106 in exactly the same manner, so that their operation need not be separately described. The pawls are indicated in Fig. 5 where the east pawl is designated 121 and the west pawl 128, while the common arm corresponding to arm 125 on the upper side is designated 129. Thus, the east ratchet 105 is driven an amount proportional to the easterly component of direction and the west ratchet 106 is driven an amount proportional to the westerly direction of movement.

Counter drive mechanism.—The movement of the four ratchets is transmitted through mechanism to a pencil or scribe to control the movement thereof for tracing the course of the vehicle on a suitable map. The component of movements is also transmitted to counters for separately registering and indicating the extent of movement of the vehicle in the several directions as will now be described.

Referring specifically to Fig. 10, the north ratchet 100 is pinned to a vertical rod which has a gear 130 pinned to its upper end (see also Fig. 2). Gear 130 drives gear 131 and meshes with a gear 132 which in turn through gear 133 drives gear 134. Gear 134 drives gear 135 integral with one of the pair of bevel gears 136 for driving a shaft 137. Shaft 137 (Figs. 1 and 14) through gearing 138 drives a shaft 139 (see Fig. 18) which has worm and wheel connection 140 with a shaft 141, which through gears 142 (Fig. 20a) drives a counter of the well known Veedee type. Through gears 143 (Fig. 18) shaft 141 also drives a second counter in axial alignment with the first counter. The second counter is driven directly, while the first is driven through an idler so that they advance in opposite directions, that is, when one counter advances additively, the other advances subtractively.

The two counters shown in Fig. 18 are designated north and south and, when the vehicle is moving in a northerly direction, the distance so traveled is entered into the north counter while at the same time the distance is subtractively

entered into the south counter. A shutter is provided in association with each counter which is shown in Fig. 20, where it is designated 144. A finger on the shutter cooperates with the cam 145 of the highest order wheel of the counter in such manner that, when a 9 is displayed in such order indicating that a complement is registered thereon, the shutter will move into position to cover the reading line of the counter. In other words, if the vehicle has moved a certain distance north from a starting position, the south counter will be covered and the north counter exposed for reading. If in the course of travel the vehicle arrives at a point south of its starting position, the counter will have been reversed so that the south counter now has a positive reading and the north a complementary reading, in which case the shutter of the north counter will prevent reading thereof while the south counter will be exposed.

Referring back now to Fig. 10, the south ratchet 99 is integral with a gear 146 through a sleeve 147. This gear 146 (see Fig. 2) has direct driving connection to the gear 135, through gear 134, and from here drives the shaft 137 to operate the counters but in a reverse direction to that in which the counters are driven by the north ratchet 100. Directional arrows in Fig. 2 show the direction of rotation of the several gears and the shaft 137 when driven by the north ratchet through gear 130. In such case it will be noted that gear 134 rotates counterclockwise and urges the gear 146 in a clockwise direction, and that such gear is permitted to move in such direction since, if the vehicle is moving north, the south ratchet is freely rotatable. On the other hand, if the vehicle is moving south, the gear 146 will be positively driven in the counterclockwise direction, in which case the rotation of gear 134 will be reversed to in turn reverse the direction of rotation of shaft 137 and incidentally of the counters. The north ratchet at such time will be free so that the back action through the gear train will not be obstructed.

Through an exactly similar system of gearing the east-west ratchets 105, 106 drive a second pair of counters indicated in Figs. 5 and 10, in the latter of which a gear 148 is integral with the east ratchet 105 and the gear 149 is integral with the west ratchet 106. The gear train is generally designated 150 and through it the cross-shaft 151 corresponding to the shaft 137 for the north-south components is driven. This shaft 151 through gearing 150a (Fig. 14) drives a shaft 151a. The shaft 151a (Fig. 18) through worm and wheel connection 152 drives a shaft similar to shaft 141 to operate a pair of counters designated east-west in Fig. 1 in the same manner. These counters also are provided with shutters 144 to register the distance traveled in the designated directions from the starting point.

A total counter for indicating the total number of miles traveled is shown in Fig. 1, where it is designated 153. This counter is driven through a pair of bevel gears 154 which through a train of gearing 155 are driven from a shaft 156 (see also Fig. 2) wherein the extremity of this shaft has bevel gear connection 157 (see also Fig. 10) with one of the gears of the train designated 115 which, as previously explained, is directly driven from the driving cable 107. The total counter 153 is thus directly driven from the driving motor or wheels of the vehicle and gives a direct odometer indication of the total miles traveled.

Resetting of the total counter 153 is, through

bevel gearing 173 (Fig. 1) operated by a knob 174. Resetting of the component counter is effected by rotation of a gear 175 (Fig. 18) by means of a suitable handle. This gear 175 has driving connection for concurrently rotating the axle shafts of the four counters. Prior to rotating gear 175 a lever 176 is manually rocked clockwise, as viewed in Fig. 18 about its pivot 177 whereby its upper end will draw the counter axle shafts 179 to the right against springs 180. This action, in the usual manner, couples the counter wheels, internally, to the shaft 179 so that as the shaft is then rotated the wheels will be reset to zero.

Transmission mechanism.—Referring now to Fig. 2, the gear 132 as explained is driven counterclockwise when the vehicle is moving north and clockwise when the vehicle is moving south, and the corresponding gear of the chain 150 (Fig. 5) likewise rotates in one direction for easterly movement and in the opposite direction for westerly movement. Integral with the gear 132 is a bevel gear 158 and the lower gear of the chain 150 is integral with a similar bevel gear 159, which two bevel gears respectively mesh with bevels 160 and 161. Bevel 160 drives a gear 163 and bevel 161 drives a gear 162, which two gears are concentrically mounted on the same axis and each drives separate mechanism, one for controlling the movement of a pencil in one direction and the other for moving the pencil in the transverse direction.

Considering first the mechanism driven by the gear 162, this gear through a sleeve 164 drives a gear 165 (see Fig. 4) which through intermediate gearing designated 166 drives a large gear 167, the direction of drive being such that, when the vehicle is moving in a westerly direction, the direction of rotation is reversed from that when the movement of the vehicle is easterly. Integral with gear 165 is a cam 168 which cooperates with a follower 169 integral with a circular shield 170 to oscillate the shield about a normally stationary sleeve or tube 171 (see Fig. 6). Immediately adjacent the shield 170 is a settable shield 172 configured as shown in Fig. 4 which is secured to sleeve 171. Both shields have low and high portions related so that with the parts in the position shown in Fig. 4, a maximum low portion of the two shields is in coincidence. As cam 168 rotates in either direction, this amount of low opening will gradually decrease and then increase again due to the oscillation of shield 170.

Disposed in opposite openings 181 in gear 167 and lying in the plane of the gear are arms 182 pivoted at 183 to a suitable bracket arm secured to the gear. Each arm has a pin 184 extending across the shields 170 and 172 in one direction (see Fig. 6) and extending beneath the free ends of a pair of pawls 185, 186 in the opposite direction. These pawls are pivoted on gear 167 so that they rotate therewith in a clockwise direction as viewed in Fig. 8 when the vehicle is moving in a westerly direction and in a counterclockwise direction when the vehicle is moving in an easterly direction.

In the plane of pawls 186 is a ratchet 188 and in the plane of pawls 185 is a ratchet 189, the two ratchets being integral and with their teeth facing in opposite directions so that they will be driven together in the direction of rotation of gear 167. A gear 190 (Figs. 2 and 6) is also integral with the ratchets and turns therewith. If the pawls were arranged to be in constant engagement with their ratchets the gear 190 would

be driven at all times for east-west movement, in direct proportion to the distance traveled.

In order to render the device suitable in connection with various map scales, the shields 170, 172 are provided to control the pawls 185, 186 so that a greater or lesser part of the angular distance through which gear 167 travels is transmitted to gear 190. Thus, with the shields 170, 172 adjusted for maximum coincidence of their low portions, pin 184 of one pair of pawls lowers into the cuts in the shields and allows the pawls to drive the ratchets for 180 degrees and then the opposite set drives the ratchets, the two sets thus alternating in their driving action, while shield 170 oscillates to produce an averaging effect in the same manner as explained for the integrating ratchet drive.

The manner in which shield 172 is adjusted can be seen from Fig. 6 where the shield is shown as having its sleeve 171 pinned to shaft 191. Turning of knob 192, which is integral with the enlarged head 193 of the shaft 191, will position shield 172. A vernier knob 194 is provided, which when turned will turn a spring pressed rod 195 whose conical surface will rotate balls 196 within head 193 against a fixed race 197 and thereby obtain slight rotation of the shaft 191.

Attached to knob 192 is a calibrated dial 198 (Figs. 3 and 9) with which a pointer 199 cooperates to indicate the map scale for which the shield is set. This pointer is carried by a horizontally positionable shield 201 provided with a window 200 through which only one of the four circumferentially arranged sets of graduations on the dial 198 may be read. These four arcs of graduations represent four major scale ranges for which the device may be adjusted and these ranges vary in the ratio of 1 to 2.5 between successive ranges. Through transmission gearing yet to be described a scale range is selected and shield 199 accordingly adjusted to position the window 200 in line with the selected range. Then the dial 198 is rotated to bring the desired scale within the selected range into alignment with the pointer 199.

Through mechanism exactly similar to that just described, the north-south integrated movement applied to gear 158 (Fig. 5) and gear 163 is transmitted to a gear 190a (Fig. 6) which corresponds to gear 190. The detailed description of these connections may thus be omitted and their identity is indicated by designating the parts with the same reference characters as applied to the east-west mechanism followed by the suffix a.

Referring to Fig. 3, the shield 201 has a pin 203 which cooperates with a cam 204 secured to a knob 205. A spring 206 urges the shield toward the left and as knob 205 is adjusted to align its pointer with one of the four scale range numerals shown, shield 201 will shift to place its window 200 in the appropriate position for reading the related dial graduations.

The shaft 207 of knob 205 (Figs. 4 and 7) has secured thereto a disk 208 having a V notch 209 in each face into which spring pressed, pivoted clutch levers 210 enter when the notches are aligned therewith. Positioned circumferentially around the disk 208 are four sets or pairs of levers 210, one pair for each of the four positions of the disk so that any pair may be selected for alignment with the single set of V notches 209.

Each lever 210 when rocked into a notch slides a gear tooth clutch element 211, 211a, 214, 214a,

215, 215a, 216 or 216a into position for driving engagement by the gear 190 or 190a as may be traced in Fig. 2. In this figure the levers 210 farthest to the right are rocked and have effected a coupling action whereby the rotation of gear 190 is transmitted through idler 212, gear 213, gear 211, gear 214, gear 215, to gear 216 which is keyed to shaft 224. This shaft is releasably coupled to a bevel gear 217, as will be explained, and through gear 217 the east-west movement is given to the pencil or marker.

Through the second of the pair of clutches engaged, the north-south gear 190a drives idler gear 213a, gear 211a, to gear 214a which is keyed to shaft 218. This shaft is releasably coupled to a bevel gear 219 to drive the pencil in north-south direction. Referring to Fig. 7 shaft 218 has a beveled disk 220 pinned to its extremity, which normally bears against a beveled surface 221 within knob 222 under the influence of a spring 223. The knob 222 has sliding key connection with bevel gear 219 so that as shaft 218 is rotated, disk 220 drives knob 221 and it in turn drives bevel gear 219. By pressing knob 222 toward the right to the position in which it is shown in Fig. 7, the drive is disconnected so that if knob 222 is now turned it will turn bevel 219 independently of the gear connections. This is done when the pencil is initially adjusted at a selected starting position.

The east-west shaft 224 is coupled to its bevel gear 217 in an exactly similar manner through the setting knob 225 (Fig. 2).

Accordingly the bevel gears 219 and 217 are rotated in one direction or the other in accordance with the direction of movement of the vehicle and an amount proportional to the distance traveled in such direction, the proportion depending upon the ratio preselected by the setting of knobs 192 and 205.

Referring to Fig. 2, bevel gear 219, drives a rod 226 through a bevel gear 227 and bevel gear 217 drives a rod 228 through a bevel gear 229. In Figs. 3 and 22 rod 226 through a pair of gears 230 drives the north-south lead screw 231, and rod 228 through gear 232 drives a vertical rod 233 which in turn through gears 234 drives a shaft 235. Referring to Figs. 21 and 22, shaft 235 is splined and has slidable thereon a bevel gear 236 which through bevel gear 237 drives the east-west lead screw 238 which is mounted in a carriage 239.

Supported on carriage 239 and threaded for movement by the screw 238 is the pencil holder 240 which is pivoted at 241 (Fig. 24). Pencil 242 is supported in the holder in a suitable manner and bears upon the map or chart 243. Pressure applied to a finger piece 244 will rock a latch 245 about pivot 246 and rock the holder 240 clockwise about its pivot 241 to a position where latch engages the upper notch 247 in which the holder is detained and disengaged from screw 238. In such position the holder may be moved freely along the screw 238 for initial positioning, or the pencil rendered inoperative. Pressure upon finger piece 248 will rock the holder back into the position of Fig. 24.

The carriage 239 is provided with rollers 249 guided in tracks 250. Secured to the underside of the carriage is a block 251 (Fig. 23) in which is a spring pressed nut 252 through which screw 231 moves the carriage along the screw. Pressure against finger 253 in a clockwise direction as viewed in Fig. 23 will rock member 254 about pivot 255 and through pin and slot connection 256 the nut 252 will be raised out of engagement

with the screw 231, so that the carriage may be moved freely.

Extending across the carriage is a rod 257 having a gear 258 at each end which mesh with stationary racks 259 and serve to maintain the carriage in proper parallel alignment as it is advanced. Pointers 260 and 261 on the pencil holder and carriage respectively cooperate with suitable scales to aid in locating the pencil.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a navigating instrument for a vehicle, a set of four coaxial ratchets, one for each of the cardinal points of the compass, a gear coaxial with said ratchets, a driving pawl for each ratchet carried by said gear, means for operating said gear and pawls continuously in the same direction in accordance with the speed of the vehicle, shielding mechanism coaxial with said ratchets for controlling the extent of engagement of the related ratchets and pawls, and compass controlled means for selectively positioning said shielding mechanism and for oscillating the said shielding mechanism within a predetermined angle at its selected position to enable rotation of the ratchet or ratchets related to the direction of movement of the vehicle and to control the extent of movement of each.

2. In a navigating instrument for a vehicle, a ratchet wheel related to a point of the compass, a driving pawl therefor driven continuously in accordance with the speed of the vehicle, a shield for controlling the extent of engagement of the pawl and ratchet, compass controlled means for adjusting said shield to expose a predetermined portion of the ratchet to the pawl for a given compass direction, and effective upon initial adjustment of the shield for altering its adjustment to repeatedly expose a greater and then a lesser portion of the ratchet than said predetermined portion, whereby the pawl's engagement will vary to produce an average ratchet movement for a given direction over a period of time.

3. In a navigating instrument for a vehicle, a pair of concentric ratchet wheels, a disk coaxial therewith, a pair of pawls carried by said disk, one pawl for each ratchet, said disk being driven continuously in accordance with the speed of the vehicle, a fixed shield configured to expose a portion of the periphery of the ratchets for engagement by the pawls at two diametrically opposite positions, a positionable shield settable to render the fixed shield effective at either or neither of its ratchet exposing positions, means for setting said positionable shield, and further means for causing the pawls to engage the exposed periphery of their related ratchets at only said diametrically opposite positions of exposure, whereby only one of the ratchets will be driven.

4. In a navigating instrument for a vehicle, a toothed ratchet wheel, a driving pawl cooperating therewith, means for continuously driving said pawl in accordance with the speed of the vehicle, compass controlled means for rendering

said wheel responsive to the action of said pawl through a predetermined amplitude for a given direction of the vehicle, and means for alternately and repeatedly increasing and decreasing said amplitude.

5. In a navigating instrument for a vehicle, a toothed ratchet wheel, a continuously moving driving pawl, a pair of shields for controlling the extent of driving engagement between the pawl and ratchet, compass controlled means for adjusting the relative positions of said shields for a given direction of the vehicle to cause the pawl to drive said ratchet an integral number of teeth, and means for repeatedly adjusting said shields to cause the pawl to drive the ratchet alternately said number of integral teeth plus and minus a fractional tooth space.

6. In a navigating instrument for a vehicle, a toothed ratchet wheel, a constantly driving pawl, a shield mechanism for effecting coupling and uncoupling of the pawl and ratchet and compass controlled means for repeatedly adjusting said shield mechanism for a given direction to render the pawl effective to drive the ratchet over a predetermined amplitude range, whereby an average extent of drive will be effective over a given period of time.

7. In a navigating instrument for vehicles having integrating mechanism controlled by distance and directional devices, the combination with a shaft rotated by said integrating mechanism at a speed proportional to the speed of the vehicle and for a period proportional to the component of the vehicle's direction, an element driven by said shaft, and connections between the shaft and said element comprising a ratchet geared to the element, a pawl driven by the shaft, and camming mechanism also driven by the shaft for controlling the period of engagement of said pawl and ratchet.

8. The invention set forth in claim 7, in which manually settable camming means is provided to variably limit the period of pawl and ratchet engagement, whereby the element will be driven at a variable ratio.

9. In a navigating instrument for vehicles having integrating mechanism controlled by distance and directional devices, the combination of a shaft rotated by said integrating mechanism at a speed proportional to the speed of the vehicle in the direction of one of the points of the compass, a ratchet, a driving pawl engageable with the ratchet and driven by said shaft, a settable

shield mechanism for controlling the period of engagement of the pawl and ratchet, means controlled by the shaft for repeatedly varying the setting of said shield mechanism over a predetermined amplitude to effect an averaging driving connection between the pawl and ratchet, and an element driven by said ratchet.

10. The invention set forth in claim 9, in which manually adjustable means is provided to select the extent to which the pawl will drive the ratchet, said averaging means being effective in the same manner for each setting of said adjustable means.

11. The invention set forth in claim 9, in which a gear train is provided, said gear train having an input member driven by the ratchet and an output member driving the element, and means for selectively controlling the driving ratio from the output member to the input member, said ratios varying in a geometric sequence.

CLAIR D. LAKE,
GEORGE F. DALY.
